FLASHLIGHT ATTACHMENT FOR GUNS

Harry H. Jahncke, Webster City, Iowa

Application February 25, 1948, Serial No. 10,663

2 Claims. (Cl. 248—229)

1

This invention relates generally to night seeing devices for fire arms and in particular to an attachment for supporting a flash light on the barrel or breech of a gun.

An object of this invention is to provide an improved flash light supporting attachment for a gun.

Another object of this invention is to provide a flash light attachment for a gun which is readily adjusted to focus a light pattern in a proper relation with the sights on the gun barrel.

Yet another object of this invention is to provide a flash light attachment for a gun which is of a construction capable of positively supporting the light on the barrel or breech of the gun against movement out of an adjusted position as a result of a firing of the gun.

Another object of this invention is to provide a flash light attachment for a gun in which means for adjusting the flash light for a tilting and rotatable movement and for up and down movement relative to the gun, are locked in an adjusted position by a single locking member.

A feature of this invention is found in the provision of a flash light attachment for the breech of a gun which includes a U-shape clamp member adapted to receive the breech of the gun in a seated position between the legs thereof. A flash light bracket, extended longitudinally of the breech, is swively mounted on an adjustable member which is supported for up and down movement on one of the legs of the clamp member. The adjustable member is constructed relative to the swivel mounting for the flash light bracket such that a single locking means is adapted to lock the flash light bracket and the adjustable member in an adjusted position against movement relative to each other and to the clamp member.

Further objects, features and advantages of this invention will become apparent from the following description when taken in connection with the accompanying drawings in which:

Fig. 1 is a perspective view of the flash light attachment of this invention;

Fig. 2 is an enlarged side elevational view of the attachment looking generally toward the right in Fig. 1;

Figs. 3 and 4 are sectional views taken along the lines 3—3 and 4—4, respectively, in Fig. 2.

With reference to the drawings, the flash light attachment of this invention is shown in Fig. 1 as including a U-shape body member 10, a pair of separable block members 11 and 12, and a flash light holding bracket 13.

2

One leg 14, of the U-member 10, is of a shorter length than its other leg 16 (Figs. 1 and 4). The base or connecting section 17 between the legs 14 and 16, lies in a plane normal to the planes of the legs 14 and 16, and has its top or inner surface formed with a transverse arcuately shaped recess 18 adapted to receive the underside of a gun breech, indicated in dotted lines as 19, in a seated position. A pair of clamping screws 21, threadable through the short leg 14 of the U-member 10, are engageable with the gun breech to clamp the same between the legs 14 and 16.

It is seen, therefore, that the legs 14 and 16 are in a straddled relation with the breech 19 and that the leg 16 is of a length to extend upwardly to substantially the top side of the breech. Also, with the breech seated within the recess 18, the base 17 is arranged in a plane parallel to the longitudinal axis of the barrel, to in turn provide for the legs being projected upwardly at right angles to such axis. It is apparent, of course, that the body member 10 may be supported in a like manner on the gun barrel 19a.

The long leg 16 is formed in its outer side with a vertically extended guideway 22 (Figs. 3 and 4). A stud 23 is projected laterally outwardly from the leg 16 and is located within the guideway 22 at a position intermediate the ends of the leg 16. A clamping nut 24 is threadable on the outer end of the stud 23.

The separable block members 11 and 12 are arranged in a side-by-side relation (Figs. 3 and 4), with the block 11 being adapted for slidable up and down movement within the guideway 22. Longitudinally extended slots or openings 26 are formed in the blocks 11 and 12 so as to be in relative alignment and are of a size to loosely receive the stud 23.

The adjacent sides 27 and 28 of the blocks 11 and 12, respectively, are formed at their upper ends with mating or corresponding half socket portions 29 which are open at the top sides of the blocks, as shown at 31 (Fig. 4). A ball member 32, receivable within the socket formed by the socket halves 29, is provided with a stem or projection 33 which extends upwardly from the block members through the socket opening 31.

The bracket structure 13 for holding a flash light 34, shown in dotted lines in Fig. 1, comprises a longitudinally extended frame member 36 and a pair of clamping rings 37 secured to the opposite ends of the frame member 36. The rings 37 are of a usual split type having hinge connections 38 and clamping screws 39. The free or outer

end of the ball projection 33 is suitably secured to the frame member 36, between the ends thereof, by means such as welding or the like.

With the clamping nut 24 in a loosened position, the block members 11 and 12 are movable apart from each other to release the block 11 for a free up and down movement within the guideway 22 in the leg 16, which constitutes an upright stationary support. The adjustable up and down movement of the block member 11 takes place within limits defined by the length of the slots 26. By virtue of the location of the ball 32 within the socket portions 29, the block 12 and the ball 32 are connected with the block 11 for up and down movement therewith. Also the separation of the blocks 11 and 12 opens the socket for the ball 32, whereby the ball is free for a swivel movement within the socket.

On tightening of the nut 24, the blocks 11 and 12 are clamped together in an adjusted position against the leg or upright support 16. As a result of this clamping action, the ball 32 is frictionally secured in an adjusted position between the socket portions 29. To assure the frictional holding of the ball between the blocks 11 and 12, the inner side 28 of the block 12 is provided with a pair of spaced pads 41 (Figs. 3 and 4) which function as a fulcrum to pivot the block 12 about its lower end, after the pads have been moved into engagement with the block 11, whereby the upper end of the block 12 is positively moved against the ball 32.

In the use of the flashlight attachment, the flashlight 34, which is of a usual cylindrically shaped type, is clamped within the rings 37. The nut 24 is then loosened sufficiently to provide for an adjustment of the blocks 11 and 12 and the ball 32 in the manner above described. Through the adjustment of the blocks, the flashlight is adjustable in an up and down direction relative to the gun breech 19. The adjustment of the ball 32 permits the flashlight to be tilted in any direction, and to be rotated about the axis of the ball projection 33 in any tilted position therefor. As a result a complete adjustment of the flashlight 34 is accomplished to provide for the light pattern or beam therefrom being directed in a path corresponding to the shot pattern of the gun. The adjusted position of the flashlight 34 is positively maintained by merely tightening the single nut 24.

From a consideration of the above description, it is seen that the invention provides a flashlight attachment which is of a simple and compact construction and readily secured in a predetermined relation on the barrel or breech of a gun. By merely loosening the clamping nut 24, the flashlight 34 is concurrently adjustable in an up and down direction, tiltably adjusted in any direction, and rotatably adjustable in any tilted position therefor. The final adjusted position of the flashlight is maintained by tightening the nut 24.

Although the invention has been described and

illustrated with respect to a preferred embodiment thereof, it is to be understood that it is not to be so limited, since changes and modifications can be made therein which are within the full intended scope of this invention, as defined by the appended claims.

I claim:

1. An attachment for supporting a flash light on the breech of a gun comprising, a U-shape member having the top surface of its base portion formed with an arcuate recess to receive the breech therein, clamp means on said U-member for clamping the breech between the legs thereof, a pair of separable members adjustably supported on one of said legs for up and down movement, with the upper adjacent sides of said separable members being formed with mating halves of a socket portion, a ball member adjustably carried in said socket portion having an upright projection extended upwardly from said separable members, means for clamping said separable members together against movement relative to said one leg of the U-member, with said clamping action providing for the ball member being frictionally held in an adjusted position within said socket portion, and a bracket structure for holding the flash light mounted on said upright projection.

2. A flash light attachment for the breech of a gun comprising, an upright support, means for clamping said support against one side of the breech in a vertical plane parallel with the longitudinal axis of said breech, a laterally extended threaded projection on said support, a pair of laterally separable members formed with aligned upright slots to receive said lateral projection therethrough, means guidably supporting one of said separable members on said support for up and down movement, a ball member, with the adjacent sides at the upper ends of said separable members being formed with mating socket portions for receiving said ball member therein, an upright projection on said ball member extended upwardly from between the adjacent sides of said separable members, a bracket structure for holding the flash light mounted on said upright projection, and a clamp member threaded on said lateral projection for clamping said separable members together in an adjusted position relative to said support, and said ball member frictionally within said socket portions.
